UNITED STATES PATENT OFFICE.

EDOUARD WÜTHRICH, OF VEYTAUX, SWITZERLAND.

CHRONOMETER-ESCAPEMENT.

SPECIFICATION forming part of Letters Patent No. 451,630, dated May 5, 1891.

Application filed November 3, 1890. Serial No. 370,144. (No model.) Patented in Switzerland April 24, 1890, No. 2,035.

To all whom it may concern:

Be it known that I, EDOUARD WÜTHRICH, watch-maker, of Veytaux, Switzerland, have invented an Improved Detent-Escapement, 5 (for which I have obtained Letters Patent in Switzerland, No. 2,035, dated April 24, 1890,) of which the following is a specification.

The main object of the improved detent-escapement for watches, which forms the present claim for patent, is to have the seconds-hand mark the dead seconds—that is to say, jumping from second to second without any other mechanism, such jumping being only due to the escapement described below. The latter is so combined that the seconds-hand remains motionless during three oscillations of the balance-wheel and jumps at the fourth one.

In the drawings, Figures 1, 2, and 3 show at an exaggerated scale three different positions of the escapement. Fig. 4 shows at about natural size the general disposition of a watch-movement provided with my escapement. Fig. 5 shows an elevation of the axle 25 A of the balance-wheel, and Fig. 6 shows in elevation the axle X of the detent D and its bridge G. Figs. 7, 8, and 9 are diagrams showing some of the parts in positions corresponding to Figs. 1, 2, and 3 more clearly.

30 In all the figures the same letters refer to the same pieces.

The escapement-wheel R is provided with a double range of teeth, the one being composed of radial teeth V V², &c., which play as 35 stopping-teeth, and of vertical teeth W' W², &c., which are intended to give an impulse to the balance-wheel at every fourth oscillation of the latter. The teeth V of the wheel R bear against the axis X of the detent D during the rest or pause of said wheel R. The axis X is provided with a suitable notch x, intended to give passage to the teeth V of wheel R when the detent D is in a certain position. A spiral spring S, fixed to the lower 40 end of the axis X, causes the detent D to be turned in the direction of the arrow a b in Figs. 1 and 7. To that end of the detent D next to the axis A of the balance-wheel B there is pivoted a star-piece E, having four 45 arms or points e', e², e³, and e⁴. The arm or point e³ bears against a pin g of the detent D, and the arm or point e⁴ is acted upon by a

weak spring F, which causes the star-piece E to remain in the position it occupies with regard to the detent D in Figs. 1, 2, 7, and 55 8, in which e³ bears against the pin g. The arms or points e' and e² of the star-piece E bear successively from left to right against the axis A of the balance-wheel under the action of the spring S, and they successively 60 escape from left to right when the notch C of the axis A is placed in front of them on the left rotation of said axis in the direction of the arrow 4.

d is a balance-weight fixed to the outer end 65 of the detent D and counterbalancing the weight of the star-piece E. The arm Z of the axis X is placed in the path of the teeth W of the wheel R, and is intended to be withdrawn by such teeth, so as to place the detent 70 D into its rest position.

T is a disk or plate fixed to the axis A of the balance-wheel, provided with a stone or projection H, receiving the impulse of the teeth W of wheel R. 75

The escapement plays as follows: As already mentioned, the balance-wheel fulfills four oscillation in every second, two left oscillations producing the successive escapement of the points e' and e² of the detent D, 80 and two right oscillations during which the escapement remains immovable. If I consider as first that oscillation of the balance-wheel which causes the escapement of the first point e' without any movement of the 85 escapement-wheel, the position of the pieces at that moment will be that shown in full lines in Fig. 1. The position of the detent D is marked d', and the balance-wheel oscillates at that moment to the left, (full line, arrow 4, in Figs. 1 and 7.) Under the action of the spiral spring S, Fig. 6, the detent D bears with its point e' against the axis A of the balance B. During this left oscillation of the balance-wheel the slot C passes in front of the point e', and the latter moves to the right of the axis A before the end of the oscillation. At the same time the point e² rests upon a full part of the axis A and remains bearing against said axis, as e' did before. 90 The parts of the escapement are then placed in the position shown in full lines in Figs. 2 and 8 and marked d², and the balance-wheel begins its right oscillation, (full line, 95 100)

arrow 3, in Figs. 2 and 8.) This right oscillation of the balance-wheel, as well as all the subsequent right oscillations of the same, is fulfilled without any displacing of the escapement-pieces, the tooth V' of wheel R remaining bearing against the axis X and the axis A, allowing no displacing of the detent D and of its axis X when the axis A turns to the right, such displacing being only possible when the axis A turns to the left and presents its slot C to the point e' or e^2 , respectively. At the third oscillation of the balance-wheel the point e^2 escapes through the slot C, and the detent D takes the position shown in dotted lines and marked d^3 in Figs. 1, 3, and 9. In this position of the detent D the notch x allows the tooth V' of wheel R to escape, and this causes at a time an impulse to be given by the tooth W^3 to the stone or projection H—that is to say, to the balance-wheel—and the meeting of the tooth W^2 with the arm Z of the axis X, causing the latter and the detent D, fixed to the same, to be placed into the position d^4 , (shown in full lines in Figs. 3 and 9,) in which the star-piece E oscillates about its pivot in compressing the spring F until it escapes from the axis A, (see d^4 in Figs. 3 and 9,) which occurs when the tooth W^2 has moved the arm Z so as to place the detent D into the position marked d^5 in Fig. 3. The tooth V^2 falls then against the axis X, the arm Z escapes from the tooth W^2 , and the arm e' of the star-piece E falls back against the axis A into that position which I took as the starting-point, and which is shown in Fig. 1 and marked d' . At that moment the third oscillation is fulfilled and a right oscillation begins, during which, as already stated, no displacing of the escapement takes place. Then the whole function begins again. The de-

scribed escapement might also be executed so as to have the balance-wheel receiving an impulse at every second oscillation. To that effect it would be sufficient to suppress one of the points e' or e^2 and to double the number of teeth of the escapement-wheel; but then the seconds-hand will jump twice in each second and will not strike the dead second. 45

The disposition of the parts of the escapement is as follows: One places the teeth of the escapement-wheel so as to have the straight line passing through the geometrical axis of the detent and through the geometrical axis of the escapement-wheel, passing in the midst of the distance between two teeth W' and W^2 , Fig. 1, when the tooth V' bears against the axis X of the detent D. The axis of the balance-wheel is placed upon a radius of wheel R, passing at one-quarter of the distance from W^3 to W^2 , this having the effect 50 to have the tooth W^3 striking the stone H before the tooth W^2 strikes the arm Z of the axis X. 55

Having thus described my invention, I claim— 65

In a watch-escapement, the detent D, with spiral spring S and star-piece E, spring F, and the axis of the detent D, having a notch x and an arm Z, in combination with a wheel R, having teeth V' V^2 , &c., and W' W^2 , &c., 70 and with a balance-wheel axis A, having a slot C, substantially as and for the purpose specified.

In testimony whereof I have signed my name to this specification in the presence of 75 two subscribing witnesses.

EDOUARD WÜTHIRICH. [L. S.]
